HOLDER FOR FLUORESCENT LAMPS

Eugene R. Kulka, Mount Vernon, N. Y.

Application March 17, 1945, Serial No. 583,221

1 Claim. (Cl. 315—96)

1

My invention relates to a new and improved holder for fluorescent lamps and their starters.

I provide a holder unit which comprises a holder-casing which has two lamp-sockets, and a starter-casing socket. Each lamp-socket can receive a pair of prongs of a lamp. The starter-casing socket can receive the two prongs of a starter-casing. The front and rear walls of said holder-casing are perforated, so that the two prongs of the starter-casing can be inserted through said front wall or through said rear wall.

Two said holder-casings can be fixed to the wall or walls of a fixture, with the front walls of said holder-casings proximate to each other. The fixture wall or walls are perforated, so that the starter-casings can be inserted through the holes of said fixture walls, if the prongs of the starter-casings are to be inserted through the rear walls of the holder-casing.

I thus provide an improved holder-casing which requires a minimum number of fastening devices and conducting parts. Two said holder-casings can hold two fluorescent lamps in absolute parallelism, and with their prongs making good electrical contact with said conducting parts of the holder-casings.

Numerous additional objects and advantages of my invention are stated in the annexed description and drawings, which illustrate an embodiment thereof.

Fig. 1 is a top plan view, which shows a single holder-casing or unit-casing of one unit, assembled at its front face with two fluorescent lamps, parts of which are illustrated. This figure also shows the wall of a fixture. The starter-casing is assembled with the holder-casing or unit-casing at the rear wall of said holder-casing, in the full line position of said starter-casing.

The broken-line position of the starter-casing shows it assembled with the unit-casing, at the front wall of said unit-casing.

Fig. 2 is a rear elevation of a unit-casing, taken at its rear wall, with the insulating cover removed.

Fig. 3 is similar to Fig. 2, on a smaller scale than Fig. 2, showing the insulating covering strip in position.

Fig. 4 is a front elevation of a unit.

Fig. 5 is a circuit diagram.

Each unit comprises a unit-casing 3 which is made of insulating material. The general construction of a holder for the prongs of a fluorescent lamp, and also for the starter-casing of such lamp, is shown in U. S. Patent No. 2,319,693, dated May 18, 1943, and U. S. Patent No. 2,363,734,

dated November 28, 1944. Hence well-known details are not illustrated herein.

Each unit-casing 3 has end lamp-sockets 4 and 5, and an intermediate starter-casing-socket 14. These sockets 4, 5 and 14 are often designated as holders, since their springs conductively abut and releasably hold a respective pair of prongs.

Each longitudinally-disposed fluorescent lamp 1 and 2 has respective metal heads 1a and 2a, at each end of each said lamp. Each metal head 2a has a pair of longitudinal prongs 2p, and each metal head 1a has a pair of longitudinal prongs 1p. These prongs are parallel to each other and to the parallel longitudinal axes of the lamps 1 and 2.

Socket 4 has blade contact springs 6 and 7. Socket 5 has blade contact springs 10 and 12.

Contact spring 12 has an integral blade-spring leg or spring extension 12a, which is one of the two contact springs of the starter-casing socket 14. Said socket 14 has a companion blade-spring 15.

Said springs, including leg 12a, are located between the front and rear walls of the unit-casing 3.

These springs are fixed to the walls of their respective sockets. Each of the springs 6, 7, 10 and 12, is provided with a respective free end in its respective socket.

The rear wall of such unit-casing 3 has a cover 17, which is made of insulating material. Cover 17 is fixed to unit-casing 3, at its rear wall, by rivets or other fasteners 18, which are located in bores or recesses 19 of unit-casing 3.

Each unit-casing 3 has a pair of transverse through-and-through holes H, through which fasteners can be inserted, in order to fix a unit-casing 3 to the wall of a respective fixture F.

At the starter-socket 14, the casing 3 has a pair of transverse through-and-through openings 24 and 25, so that these holes extend through the front and rear walls of said casing 3. These holes 24 and 25 register with corresponding holes in the insulating cover 17.

Each unit-casing 3 is associated with four lead-wires 8, 9, 16 and 11. Each said wire has the usual insulating covering. The rear wall of each unit-casing 3 has the usual recesses, through which the covered portions of said wires can be respectively inserted. The inner end of each said lead-wire 8, 9, 16 and 11 is bare. Said bare ends are respectively conductively fixed to the springs 6, 7, 15, and 19, at 6a, 7a, 16a, and 10a. This

can be done by soldering, brazing, by mechanical connecting means, or in any manner.

Two such unit-casings 3 are fixed with their front walls parallel and facing each other to the wall or walls of a fixture or fixtures, so that said casings have then front walls proximate to each other and exposed.

Fig. 1 shows the wall of a fixture F. Said wall has an opening, through which the respective starter-casing C can be inserted, in order to assemble said starter-casing C with the respective unit-casing 3, at the rear wall of said unit-casing 3. The two prongs of the starter-casing C are then inserted through the two holes of the cover 17, which register with the rear ends of openings 24 and 25.

Said starter casing C can be assembled with the respective unit-casing 3, at the front wall of said unit-casing 3, as shown in broken lines in Fig. 1. In such position, the starter-casing C is located between the lamps 1 and 2. In such case, the two prongs of the starter-casing C are inserted into openings 24 and 25, through the front wall of the casing 3.

The two prongs of each lamp are conductively assembled with a respective pair of springs 6, 7, or 10, 12, in the usual manner. For this purpose, each unit-casing 3 is provided with the usual inlet-recesses 20 and 21, through each of which two respective associated lamp-prongs can be passed. The front wall of each lamp-socket 4 and 5 also has the usual openings 22 and 23, in which parts of the respective blade-springs are exposed.

When two unit-casings 3 are assembled in order to hold a pair of lamps, the lamp-socket 4 of each unit-casing 3 is located diagonally relative to the lamp socket 4 of the other unit-casing 3, as shown in Fig. 5.

Each lamp of the pair of lamps 1 and 2, has its respective starter-casing C. For example, the starter-casing C which is assembled with the unit-casing 3 which is shown in Fig. 1, is combined with the lamp 2. The other starter-casing C which is assembled with the other unit-casing 3, is combined with lamp 1, because the socket 4 of the unit-casing 3 which is shown in Fig. 1, will be longitudinally aligned with the socket 5 of the companion unit-casing 3.

As disclosed in said U. S. Patent No. 2,363,834, the starter-casing C has a pair of prongs, which are inserted into openings 24 and 25, and the starter-casing 3 is then turned, so that its prongs are held releasably by the respective resilient leg 12a and the respective companion spring 15.

Each opening 24 and 25 has a narrow portion and a wide portion. The two prongs of each starter-casing C are originally longitudinally inserted into said narrow portions. Thus, when the prongs of a starter-casing C are originally longitudinally inserted into the openings 24 and 25, in the full-line position of said starter-casing C which is shown in Fig. 2, said starter-casing C is then turned clockwise, so that its prongs are yieldingly held by leg 12a and spring 15.

I thus provide a unit-casing 3, which requires only four lead-wires 8, 9, 16, and 11, whereas if said three sockets 4, 5, and 14 were made as three separate parts, according to current practice, six such lead wires would be required.

The improved unit-casing 3 requires only two attaching holes H, whereas six such holes would be necessary if said sockets 4, 5 and 14 were made as separate pieces.

Likewise, the lamps 1 and 2 are held in absolute parallelism, thus ensuring good conductive

contact between the four prongs of each lamp, and the respective springs 6, 7 and 10, 12.

In many cases, the fixture has a glass covering. According to current practice, it is necessary to locate the starter-casing inwardly of said glass cover, so that the cover must be removed and replaced, in order to replace a starter. This time and expense is eliminated, by locating the starter-casing C as shown in full lines in Fig. 1.

In many cases, the fluorescent lamps are mounted in industrial fixtures, which are located back-to-back. In such case, the starter-casings C can be located as shown in broken lines in Fig. 1.

I thus greatly reduce the cost of making and using holders for fluorescent lamps and the like, which require starting switches.

Fig. 5 shows the circuit of the lamps 1 and 2.

In a lamp of this type, each end of the lamp is provided with a starting filament, whose ends are connected to the respective pair of prongs. When the lamp is connected and while it is cold, its two end filaments are temporarily connected by a starter switch to the respective terminals of the source of alternating current. The starter switch is automatic and it is operated by a thermostat, to open the connection between the two resistances or coils, as soon as the lamp is sufficiently heated for the ionization discharge through its filling. The filaments then act as electrodes for the ionization discharge.

Fig. 5 shows the springs 10, 12, 7, and 6 of the holder which is shown in Fig. 1, and the springs 6d, 7d, 12d, and 10d of the companion holder. Springs 6d and 7d are identical with springs 6 and 7, and springs 12d and 10d are identical with springs 12 and 10. Spring 12d has an extension 12b, which corresponds to extension 12a. Spring 15d corresponds to spring 15. Fig. 5 shows that the leg 12a of spring 12 forms one terminal of a starter switch 2s, which is associated with the respective left lamp 2. The leg 12b forms one of the terminals of starter switch 1s, which is associated with the right lamp 1.

Switch 1s has a blade 53a, and switch 2s has a blade 53. Said blades are biased to close the respective starter switches 1s and 2s.

The four left lamp prongs 2p of lamp 2, respectively contact with the respective four springs 6d, 7d, 10 and 12.

The four lamp prongs 1p of the right lamp 1, contact respectively with the respective four springs 12d, 10d, 7, and 6.

The lamp 2 has the two filaments 2c, and the lamp 1 has the two filaments 1c. Each said filament closes the circuit between the respective pair of prongs.

One lead 51 of the alternating current power line is connected to the usual ballast resistance 54, which has two equal legs.

Wire 11 connects spring 10 to one leg of said ballast resistance 54. Wire 8 connects spring 6 to the other leg of ballast resistance 54.

The other lead 50 of said alternating current power line is connected by wire 8d to spring 6d, and by wire 11d to spring 10d. Wires 11 and 11d correspond to each other, and wires 8 and 8d correspond to each other.

Wire 9, which is connected to spring 7, is spliced at 52 to the wire 16d which is connected to spring 15d of starter switch 1s. Wire 16, which is connected to the spring or blade 15, is spliced at 53 to wire 9d, which is connected to spring 1d.

When lamp 2 is started, it is cold, and the starter blade 53 of its starter switch 2s, which is located in the respective starter casing C, closes

the circuit between spring or blade 15 and spring or blade 12a. The current passes, for example, from lead 50, through wire 8d, spring 6d, the respective prong 2p, the respective filament 2c, the other respective prong 2p, spring 7d, wires 9d and 16 to spring 15, through starter blade 53 and leg 12a to spring 12, through the respective prong 2p, the respective filament 2c and the other respective prong 2p to spring 10, wire 11, one leg of ballast resistance 54, and to the other lead 51.

When the lamp 2 is sufficiently heated, a thermal device automatically moves blade 53 to open the circuit between spring 15 and leg 12a. The current is then conducted through lamp 2, by ionization through the gaseous and vapor filling between the filaments 2c, which then act as electrodes.

The blade 53a of the starter switch 1s, similarly automatically breaks the circuit between the filaments 1c of lamp 1, when said lamp 1 is sufficiently heated for the ionization discharge through its filling.

In practice, each starter switch and its thermostat is located in a respective casing C.

For convenience, each end 4 and 5 of the casing 3, in which a pair of springs 6, 7, or 10, 12 are located, is designated as a lamp-prong-socket. The intermediate part 14 of the casing 3 is designated as the starter-casing-prong-socket.

The lamp-prong-socket contact 1d of holder casing 3, which is connected to a contact of the starter-casing-prong-socket of the other holder casing 3, is unconnected to the contacts of the starter-casing-prong-socket of the respective holder casing 3.

For convenience, the members 10, 12, 7 and 6 are designated as one series of terminal members, and the members 6d, 7d, 12d and 10d are designated as another series of terminal members. Each said series has two outer terminal members, as the members 10 and 6, and two intermediate inner terminal members, as the members 12 and 7.

The outer terminal members 10 and 6 of one series are connected to a respective power-main 51, and the outer terminal members 6d and 10d of the other series are connected to another respective power-main 50. The inner terminal member 12 of one series is diagonally opposed to the inner terminal member 12d of the other series. These diagonally opposed inner terminal members 12 and 12d have respective terminal extensions 12a and 12b.

Each lamp has an associated thermal starter switch. One starter switch, which has the thermally controlled switch blade 53, has one end thereof contacting the external starter-switch contact-member 2p of the respective lamp, and said switch-blade 53 normally contacts the associated terminal extension 12a of the same lamp, when said lamp is cold. The other starter switch, which has the movable switch blade 53a, is similarly associated with the other lamp.

The outer contact members 2p are designated as power-main contact-members.

I have disclosed a preferred embodiment of my invention, but it is clear that numerous changes and omissions and additions can be made without departing from its scope.

I claim:

In combination, a pair of parallel holder casings, each holder casing having a pair of lamp sockets and a starter-casing-socket which is located between said lamp sockets, said holder cas-

ings being spaced longitudinally from each other along a longitudinal axis which extends through said starter-casing-sockets and being perpendicular to said longitudinal axis, each lamp socket 5 of one holder casing being longitudinally aligned with a lamp socket of the other holder casing to provide a respective longitudinally aligned pair of lamp sockets, each lamp socket having an outer contact blade and an inner contact blade, only one inner contact blade of each lamp socket being an extended blade which is laterally extended towards the other inner contact blade of the respective holder casing into said starter-casing-socket to provide an additional contact blade 10 in said starter-casing-socket, each said starter-casing-socket having a supplemental contact blade, said laterally extended inner blades being on opposite sides of said longitudinal axis, the two outer contact blades of one holder casing 20 being connected to one power main of a source of alternating current, the two outer contact blades of the other holder casing being connected to the other power main of said source of alternating current, a starter-casing located in each 25 said starter-casing-socket and having respective contacts which respectively contact with the respective additional contact blade and the respective supplemental contact blade, each said starter-casing having a movable and thermally controlled starter switch-blade which is permanently connected to the respective supplemental contact blade and which is biased to normally contact with the respective additional contact blade, the other and non-extended inner blade of each said 30 35 holder casing being connected to the supplemental blade of the starter-casing socket of the other holder casing, two longitudinal ionic discharge lamps, each discharge lamp having a pair of external contact prongs at each end thereof and a filament connected between each said pair of contact prongs, each said lamp having a pair of said contact prongs located and held in a respective pair of longitudinally aligned lamp sockets with each pair of external prongs contacting with a respective outer contact blade and an inner contact blade, said switch blades being movable to break the circuit between said additional contact blades and said supplemental contact blades when said lamps are sufficiently heated 40 45 50 for direct discharge between their respective filaments.

EUGENE R. KULKA.
